Fig. 7

FIG. 1 is a side elevation of a fountain brush embodying my new design;

FIG. 2 is a top plan view thereof;

FIGS. 3 and 4 are front and rear elevations, respectively, with the portions shown in broken lines in FIGS. 1 and 2 omitted from FIG. 4 for convenience of illustration only;

FIG. 5 is an enlarged fragmentary cross sectional view on the line V—V of FIG. 1, illustrating the textured surface ornamentation appearing on the sides of the valve fitting and valve handle;

FIG. 6 is an enlarged fragmentary cross sectional view on the line VI—VI of FIG. 2, illustrating the detail on the face of the valve handle; and

FIG. 7 is an enlarged fragmentary cross sectional view

through several of the grooves on the handle of the brush, illustrating the detail thereof.

The dominant features of the design reside in the portions shown in full lines, it being understood that the grooved pattern fragmentarily shown on the handle in FIGS. 1 and 2 covers the entire surface of the handle.

I claim:

The ornamental design for a fountain brush or the like, substantially as shown and described.
